ASH TRAY

Silvius J. Gall and Betty C. Gall, Glendale, Calif.

Application July 24, 1950, Serial No. 11,382

Term of patent 7 years

(Cl. D85—2)

To all whom it may concern:

Be it known that we, Silvius J. Gall and Betty C. Gall, citizens of the United States, residing at Glendale, in the county of Los Angeles and State of California, have invented a new, original, and ornamental Design for an Ash Tray, of which the following is a specification, reference being had to the accompanying drawings, forming part thereof.

We claim:

The ornamental design for an ash tray, as shown.
